UNITED STATES PATENT OFFICE.

JOSEPH A. BERNO, OF MANSFIELD, OHIO.

RUG-DISPLAYING DEVICE.

1,320,442.

Specification of Letters Patent.

Patented Nov. 4, 1919.

Application filed November 21, 1917. Serial No. 203,219.

To all whom it may concern:

Be it known that I, JOSEPH A. BERNO, a citizen of the United States, residing at Mansfield, in the county of Richland and State of Ohio, have invented certain new and useful Improvements in Rug-Displaying Devices; and I do hereby declare the following to be a full, clear, and exact description of the invention, such as will enable others skilled in the art to which it appertains to make and use the same.

This invention relates to display apparatus and more particularly to display apparatus for rugs or the like for stores and the primary object of the invention is to provide an improved machine for displaying a number of rugs, one after the other and thus obviate the necessity of spreading the rugs on the floor of the store before a customer, 20 which litters up the floor and soils the rugs.

Another object of the invention is to provide a conveyer belt carrying a plurality of rugs or the like, which is adapted to be supported upon a pair of spaced reels, which 25 are rotated by any suitable means, such as a motor or the like.

A further object of the invention is to provide a pair of protecting casings or housings for inclosing the spaced reels, so as to 30 provide a covering for the rugs and thus prevent the same from becoming easily soiled.

A still further object of the invention is to provide an improved winding means positioned in the casing for receiving the conveyer belt, so as to provide a relatively large surface for receiving the conveyer belt and thus allowing a number of rugs to be wound on the winding means in each casing.

40 A still further object of the invention is to provide a display apparatus for rugs or the like of the above character, which is durable and efficient in use, one that is simple and easy to construct and one that can be placed upon the market at a reasonable price.

With these and other objects in view, the invention consists in the novel construction, arrangement and formation of parts, as will 50 be hereinafter more fully described and claimed and illustrated in the accompanying drawings, forming a part thereof, in which:

Figure 1 is a top plan view of the improved display apparatus, showing a rug 55 in position on the conveyer belt.

Fig. 2 is a side elevation of the improved

machine with parts of the protecting housing broken away to show the winding drums.

Fig. 3 is a longitudinal section taken 60 through the improved apparatus.

Fig. 4 is a transverse section taken on the line 4-4 of Fig. 1.

Fig. 5 is a side elevation of a modified form of the device, showing parts of the 65 protecting casing in section, and

Fig. 6 is a transverse sectional view through one of the protecting casings showing the modified form of the device.

Referring to the drawings in detail, 70 wherein similar reference numerals designate corresponding parts throughout the several views, the numeral 1 generally indicates the improved display apparatus, which includes the substantially rectangular base 75 plate 2 having spaced housings 3 mounted on its upper surface at each end thereof. Each housing 3 includes the side walls 4, rear and front walls 5 and 6 respectively and the top wall 7. Secured to the base plate 80 by suitable fastening elements 9 and positioned in each housing are a pair of spaced standards 8 which rotatably support a winding drum or reel 10. The drums 10 have stub-shafts 11 secured thereto which are 85 journaled in the upper ends of the standards. One of the stub-shafts 11, at one end of each drum protrudes beyond the supporting standard 8, as at 12, and these stub shafts have keyed to their outer ends pulley wheels 90 13. An electric reversible motor 14 is mounted on the base plate 2 in one of the casings 3 and has its drive shaft 15 provided with a relatively small gear 16 which meshes with a relatively large gear 17 keyed to a shaft 95 18 supported in a bearing 19. The outer end of the shaft 18 is provided with a pair of relatively small pulley wheels 20 and 21 respectively and a belt 22 is trained around the small pulley 21 and around the relatively large pulley 13 carried by the drum 10 adjacent thereto. A drive belt 23 is trained around the relatively small pulley 20 and the relatively large pulley wheel 13 carried by the drum 10 in the other housing 100 3 and the drive belts 22 and 23 serve to rotate the drums in the same direction.

Each of the housings 3 has its front wall 6 provided with a cut out portion 24 which extends to the base plate 2 of the apparatus. 110 A web or conveyer belt 25 extends from one winding drum to the other and has its

free end secured to each winding drum as at 26 and the web can be wound around the drums as many times as desired and when the drums are rotated the web will be rotated therewith. The web 25 can be made of any suitable material such as canvas or open netting. The conveyer belt or web 25 extends through the cut out portions 24 formed in the front walls 6 and as the belt 10 passes from one casing to the other the same is adapted to display any articles which are secured thereto. As shown, the apparatus is particularly adapted for displaying rugs and the same are adapted to be secured to 15 the web or conveyer belt 25 by any suitable means such as clips or pins and the rugs 27 are fastened in such a manner that they can be readily moved from the web when so desired. In each housing 3 and adjacent 20 the front wall 6 are a pair of spaced bearings 28 which are secured to the base plate 2 as at 29 and these bearings rotatably support a pair of vertically positioned guide rollers 30 between which the web 25 passes 25 and these rollers serve as a guiding means for winding the web and rugs 27 on the winding drums. Each of the winding drums 10 at each end thereof is provided with a guide flange 31 to prevent the web and rugs 30 from running off of the winding drums. Each of the housings 3 is provided with openings 32 for the drive belt 23 and these openings form a guide means for the belt. A suitable switch 33 is secured to one of the 35 casings 3 adjacent the motor 14, and connects with the motor by suitable wires 35 and provides means whereby the motor can be started, stopped or reversed.

Each of the housings 3 is readily re- 40 movable from the base plate 2 so that the winding drums can be readily repaired when necessary. The casings 3 may be hinged at the lower edge of their rear walls 5 to the base plate 2 if so desired so that the 45 same can be swung back on the base plate when it is desired to get into the casing.

In operation of the improved device a series of rugs 27, strips of carpet, or any other articles, that are to be displayed, are 50 secured on the web 25 by any suitable means and the switch is then operated so as to cause the motor 14 to rotate and operate the winding drums 10, which will wind the web from one drum to the other and thus as the 55 web passes from one casing to the other casing 3 the articles carried by the web will be displayed. When it is desired to rewind the web from one drum to the other the switch is operated so as to reverse the motor 60 and thus reverse the direction of the winding drums 10.

In Figs. 5 and 6 is illustrated a modified form of the rug displaying device and in these figures the winding means for receiving the conveyer belt 25 which carries the

rugs 27 are formed in such a manner so as to provide a relatively large surface for receiving the conveyer belt 25 and the rugs, so that a number of rugs can be readily wound on the winding means in each of the protecting casings 3. The standards for supporting the modified form of winding means 36 are spaced from each other and are formed relatively high and are designated by the numeral 37 and the same rotatably receive 70 a pair of spaced rollers or drums 38, which extend in direct vertical alinement with each other. And these rollers or drums have guide flanges 39 formed on their side edges which prevent the rugs and conveyer belt 80 from riding off of the same. The rollers 38 are provided with the shafts 40, which extend beyond the rollers and are journaled in the standards 37. One end of each shaft is extended beyond one of the standards as 85 at 41, for a purpose which will hereinafter more fully appear. Extending over the upper and lower rollers 38 are endless belts 42 and the conveyer 25, which carries the rugs 27 on its upper surface, is wound around the endless belt 42 and has its free ends secured thereto. The conveyer belt 25 may be wound around the endless belt as many times as is considered necessary and the endless belt 42 provides a relatively large 90 surface for the conveyer belts 25 to wind upon. The extended ends 41 of the shafts 40, which extend beyond the standard 37 receive sprocket wheels 43, which are keyed to the shafts and they receive a sprocket 100 chain 44 which is trained around the sprocket wheels and which rotates the rollers 38 simultaneously. The lower shaft 41 of one of the rollers in the casing in which the motor 15 is positioned has keyed to its 105 terminal which projects beyond the standard the relatively large pulley wheel 45, which has trained thereover the belt 22, which extends to the pulley 21 keyed on the shaft 18. The extended portion 41 of the shaft 110 40 of the lower roller positioned in the casing opposite from the one in which is positioned the motor 15, has keyed thereto the pulley wheel 46 around which is trained the driving belt 23 which extends from the other pulley 115 20 keyed on the shaft 18.

From the foregoing it can be seen that each of the winding means is driven simultaneously and each provides a relatively large surface for receiving the winding conveyer drum 25.

The modified form of the invention shown in Fig. 5 is exactly the same as in the other figures with the exception of the winding means.

In practice, I have found that the form of my invention, illustrated in the accompanying drawings and referred to in the above description, as the preferred embodiments, is the most efficient and practical; yet real- 125 130

izing the conditions concurrent with the adoption of my device will necessarily vary, I desire to emphasize the fact that various minor changes in details of construction, proportion and arrangement of parts may be resorted to, when required, without sacrificing any of the advantages of my invention as set forth.

What is claimed is:—

- 0 In a display apparatus for rugs or the like, a base plate, a housing secured to the base plate at each end thereof, a pair of spaced standards secured in each housing, a pair of spaced rollers journaled in each

pair of standards in direct vertical alignment with each other, an endless belt trained around each pair of rollers, a web connecting the endless belt trained around one of the pairs of rollers with the endless belt trained around the other pair of rollers and means 15 for rotating said rollers.

In testimony whereof I affix my signature in presence of two witnesses.

JOSEPH A. BERNO.
